THOMAS M. BEAMISH, OF VANCOUVER, BRITISH COLUMBIA, CANADA.

RAILWAY-RAIL FASTENING TO TIE.

1,165,834.

Specification of Letters Patent. Patented Dec. 28, 1915.

Application filed September 30, 1915. Serial No. 53,374.

To all whom it may concern:

Be it known that I, THOMAS M. BEAMISH, a citizen of the Dominion of Canada, residing at Vancouver, in the Province of British Columbia, Canada, have invented certain new and useful Improvements in Railway-Rail Fastenings to Ties, of which the following is a specification.

This invention relates to a means for securing a railway rail to its ties and is intended as a substitute for the customary spike by which such attachment is usually made.

With the customary spike the holding power directly depends on the frictional grip of the wood on the sides of the spike, which hold, though it may be satisfactory for a short time, becomes ineffective after a short period of use, and further the spike being vertically driven into the wood, water finds a ready entrance down the sides of the spike and decay of the wood rapidly ensues when the spike becomes practically useless as a securing means. These objections are overcome in the fastening, which is the subject of this application, wherein the flange of the rail is held to the tie by a hook member engaging its edge at each side of the tie, which hook member is angularly disposed beneath the flange of the rail, and its lower end is secured by a special spike driven into the side of the tie, which spike is tapered to draw the hook member into tight engagement as it is driven home. Such attachment is for ordinary requirements made as stated on opposite sides of the rail on opposite sides of the tie, but may be supplemented as required by one or two additional attachments on opposite sides of the flange on one or both sides of the tie.

The particular construction and application of this fastening are fully set forth in the following specification, reference being made to the drawings by which it is accompanied, in which:

Figure 1 shows the attachment of rail to tie in perspective, the full lines indicating the ordinary provision and the dot and dash lines the supplementary provision. Fig. 2 is a detail of the spike. Fig. 3 is a plan of the hook and its spike looking in the direction of the arrow in Fig. 1.

In these drawings 2 represents a standard rail and 3 a wooden tie on which the rail rests and to which it is secured. The attachment comprises a member 6 having at

one end a hook 4 adapted to engage the flange of the rail and at the other end is bent to form an open hook 5 or a closed eye adapted to receive a spike 7, two sides of the spike being parallel to the axis of the hook.

The spike 7 is formed with a square portion 8 for a short distance from its entering end and is thereafter tapered, as at 9, toward the head. This tapered portion is preferably turned toward the end of the hook or eye 5 so that it directly exercises its tightening effect on the hook engagement 4 on the rail flange.

Between the hooks 4 and 5 the body of the hook member may be flattened, as at 6. This not only strengthens it against flexure under the pull through the hook ends but enables the hook members to cross one another when a supplementary hook is applied, as shown by the dot and dash lines, while the hook end 5 is close up to the wood on the spike.

Under ordinary circumstances the rail will be secured by a hook attachment on each side of the tie 3 engaging opposite sides of the flange of the rail, but where extra security is required, as on a curve, a supplementary attachment may be applied, as shown by the dot and dash lines in Fig. 1, on opposite sides of the flange on one or both sides of the tie.

The spikes are not in the first instance driven fully in so that they may subsequently be driven in farther from time to time to take up any slackness which may exist due to wear or compression of the wood under the flange of the rail.

It will be noticed that not only has the spike a more positive hold of the wood to secure the rail to the tie than where it is driven in from the top but owing to the angle at which the hook members 4 are placed, if there is any tendency for the rail to move laterally on the tie the hook attachment draws the rail more tightly down to the tie. Further the angle at which the spike is driven into the wood, that is, obliquely across the grain of the wood, is the strongest holding position and the wood compressed by the driving of the spike is harder at 10 to resist the pull of the hook member.

As explained also in the preamble of this specification the spikes being driven in from the sides of the tie, instead of from the top, as is the present practice, water will not

tend to drain into the wood of the tie along the spike.

The spikes may be driven by hammer into the sides of the ties when they are the regulation distances apart; where the regulation number of ties per rail is increased to such an extent that the proximity of adjacent ties interferes with the hammer drive the spike may be effectively driven either by a pneumatic hammer or by a lever or screw operated cramp.

Having now particularly described my invention, I hereby declare that what I claim as new and desire to be protected in by Letters Patent, is:

1. A railway rail fastening to tie, comprising a member having a hook at one end adapted to engage the upper side of the rail flange and at the other end provision for attachment to a spike driven into the side of the tie approximately under the other edge of the rail flange which spike is wedge-shaped adjacent to its head to exercise a tightening pull on the hook member.
2. A railway rail fastening to tie, comprising the combination with a hook ended member adapted to extend angularly downward from the edge of the flange at one side of the rail to a position approximately under the other edge of the flange, of a securing spike having a parallel portion adjacent the point and thereafter tapered larger toward the head.

3. A railway rail fastening to tie, comprising a member having at one end a hook adapted to engage the upper side of the rail flange and at the other end a hook adapted to engage a spike driven into the side of the tie approximately under the opposite edge of the rail flange, said member intermediate of its ends being flattened that the hook members from opposite sides of the flange may cross one another on the same side of the tie.

In testimony whereof I affix my signature in presence of two witnesses.

THOMAS M. BEAMISH.
